Howson & Howson

UNITED STATES PATENT OFFICE.

JOHN W. LEWELLEN, OF RIDAL, PENNSYLVANIA.

OIL-FURNACE.

1,289,484.

Specification of Letters Patent. Patented Dec. 31, 1918.

Application filed February 26, 1918. Serial No. 219,274.

To all whom it may concern:

Be it known that I, JOHN W. LEWELLEN, a citizen of the United States, residing in Ridal, Montgomery county, Pennsylvania, 5 have invented the Improvement in Oil-Furnaces, of which the following is a specification.

One object of this invention is to provide a relatively simple, compact and substantial 10 form of burner which shall include such an arrangement of parts as will cause perfect combustion of liquid fuel and which shall be so constructed as to be available for use in connection with forges, ovens, kilns, hot 15 water and steam plants, or in fact for any use requiring a high degree of heat and the continued and efficient maintenance of relatively high temperatures.

It is further desired to provide an oil 20 burning device with novel means for insuring intimate contact between the air and gasified fuel with a view to securing perfect combustion, the invention also contemplating certain detail improvements in the 25 mounting, form and disposition of certain of the furnace parts.

These objects and other advantageous ends I attain as hereinafter set forth, reference being had to the accompanying drawings, in 30 which—

Figure 1 is a side elevation of a furnace or burner constructed in accordance with my invention;

Fig. 2 is a central vertical section on a 35 larger scale than Fig. 1, further illustrating the detail construction of the burner;

Fig. 3 is a horizontal section of the deflector for setting up a rotary movement of the air supplied to my burner; and

Fig. 4 is a fragmentary vertical section 40 illustrating a slightly modified form of refractory top.

In the above drawings, 1 represents a supporting frame which may be of any suitable 45 construction and which in the present instance is shown as engaging the outwardly projecting flange of a flat ring 2 constituting the top of the furnace casing. This latter consists of a cylindrical body 3 preferably 50 of sheet metal and a bottom member 4 formed by a flattened conical casting having a central flanged inlet 5 to which is connected the delivery pipe 6 of a blower 7. The latter may be of any form suitable for 55 supplying air under relatively low pressure and the conduit 6 has mounted in it a

damper 8 whereby the flow of such air may be regulated, although obviously, such regulation may be accomplished by other means such as regulation of the speed of said 60 blower.

The bottom and top members 4 and 2 with the casing body 3 are held together by a suitable number of vertically extending bolts 9 and while the heated products of combustion escaping from the casing may be directed in any of a number of ways to a point of use, I have illustrated one device for accomplishing the desired end which I have found practical and efficient. This 65 consists of a hollow refractory structure 10 having a horizontal passage 11 extending through its body and communicating with a downwardly opening inlet 12. Said structure 10 is mounted upon and in the present 70 instance, is supported by the ring 2 of the furnace casing and has a downwardly extending portion 13 fitting into and through said ring for maintaining the inlet opening 12 centrally of said casing. Said portion 75 also serves to some extent to direct the air and hot gases of combustion down into a fuel pan 18 and if desired it may be vertically extended down to within a short distance of the same as shown at 35 (Fig. 4) 80 so that the air is compelled to pass into the 85 said pan instead of in a direct line to the passage 12.

Within the casing and supported upon the bottom member 4 thereof is a deflector 90 structure 14 consisting of a series of curved vanes extended spirally outward from and arranged at equal distances around the lower end of a central conduit 15, which is mounted in and extends upwardly from the 95 bottom of a pan or shallow container 16 from whose bottom said vanes project downwardly. The deflector 14 is so proportioned that the outer ends of its blades are spaced some distance away from the inner wall of the casing body 3 and the arrangement is such that the air delivered to the casing through the inlet 5 divides, part passing vertically upward through the conduit 15 and the greater portion flowing outward in the spiral paths defined by the vanes to the annular space around the same, in which they flow upwardly. 105

Mounted upon and substantially concentric with the pan 16 (which may merely 110 contain non-circulating air or may be filled with a non-conductor of heat such as as-

bestos or mineral wool) is a second and preferably deeper pan 17 having an upwardly flanged central opening for the passage of the conduit 15 which terminates at 5 or immediately adjacent the plane or the top of this second pan. This latter has mounted within its upper portion a third pan 18 which like it, has a central opening provided with a flange fitting over the 10 flange 19 and terminating in the plane including the top of said pan 17.

This third pan 18 has a circular depression or channel 20 formed in its bottom portion concentrically with the conduit 15, for 15 the reception and distribution of the oil or other liquid fuel delivered through a supply pipe 21, which enters the top of the casing from any suitable source. A valve 22 is connected in this pipe for regulating the 20 flow of fuel therethrough and the rapid distribution of the fuel to all parts of the pan 18 is assured by reason of the narrow channel 20 into which said supply pipe discharges directly. The fuel pan preferably 25 has projecting up from its bottom one more series of concentrically arranged vanes or wings 36 designed to be heated by the flame of burning oil and to transfer the heat so received to the pan structure. Said pan 18 30 may be leveled relatively to and independently of the remainder of the structure by suitable leveling screws 23 extending through the bottom of the pan 17 and out through the casing structure, so that even 35 though the furnace as a whole may not be accurately set, it is possible to accurately adjust the position of the pan 18 so that the oil delivered thereto will be uniformly distributed over its bottom.

40 A spider or other suitable open supporting structure 24 is mounted in the upper part of the conduit 15 in position to receive the threaded spindle 25 of a circular deflecting plate 26 carried upon its top in such 45 position that air passing upwardly through said conduit is directed downwardly from the center of the pan 18 over the inner parts thereof toward the outer portions. As shown in Fig. 2 the inwardly extending 50 portion 13 of the refractory structure 10 or the part 35 of Fig. 4, is spaced a short distance away from the top of the pan 18 so that the upwardly flowing body of air around the outside of the pan 17 is deflected downwardly and inwardly over said pan 55 18 from the outer portion thereof toward the center, it being noted moreover that this air has a more or less violent rotary movement imparted to it by reason of its 60 engagement with the curved vanes of the deflector 14.

The pan 17 is provided with a substantially radial groove 27 extending downwardly from its inner portion to its outer 65 wall, for the reception of any liquid which

may overflow from the oil receiving pan 18, and a valved drain pipe 28 is extended down from the outer portion of this groove or channel through the bottom casing member 4 for conducting away any liquid which 70 may collect.

Under operating conditions oil or other liquid fuel is supplied to the pan 18 through the pipe 21 and air under pressure is delivered at what may be found to be the 75 proper rate, by operation of the fan or blower 7. The oil in the pan 18 is ignited by any suitable means and the air for its combustion is delivered from the conduit 6 between the casing body 3 and the outside 80 of the pan 17 as well as through the conduit 15. As above noted, the outer portion of this air has the rotary movement above indicated and upon meeting the downwardly and outwardly deflected body of air 85 delivered through the conduit 15 is most intimately mixed with the vapor arising from the fuel in the third pan 18 so that this is burnt in the most perfect manner with the resulting production of highly 90 heated gases which pass through the opening 12 into and out of the passage 11 of the refractory structure 10. It will of course be understood that when the device is in operation the pan 18 becomes highly heated 95 not only from the hot gases but also by the heat conducted to it by the wings 36 so that the fuel delivered thereto is rapidly vaporized. In order however, to prevent the cooling of this pan by the incoming currents of 100 air, it is insulated by the dead air space between it and the bottom of the pan 17. This latter pan may be further insulated by the pan 16 which merely contains non-circulating air or, as shown, contains some 105 non-conductor of heat such as mineral wool, asbestos or the like.

Obviously the highly heated products of combustion from my furnace may be directed or delivered in any manner suitable 110 to the work to be performed by them, and the relative amounts of air and fuel delivered may be accurately regulated by the damper 8 and the valve 22 in order that perfect combustion of the fuel will occur. 115

I claim:

1. The combination in a burner of a casing; a fuel pan having an air conduit therethrough and mounted with its sides spaced away from those of said casing to provide 120 an air passage; means for delivering liquid fuel to said pan; means for causing air under pressure to simultaneously flow up through the conduit and through said passage; with means for directing the air current from the passage and also that from the conduit to cause them to flow laterally over the top of said pan.

2. The combination in a burner of a casing; a fuel pan spaced away from the walls 130

of the casing to provide an air passage; means for delivering fuel to the pan; means for delivering air under pressure to the lower part of the casing; and a deflector 5 mounted in the casing under the pan for causing the air delivered from said means to have a rotary movement as it flows adjacent said pan.

3. The combination in a burner of a casing; a plurality of superposed pans mounted in said casing and spaced away from the vertical wall thereof; means for delivering fuel to the top pan; heat insulating material in the bottom pan positioned to prevent conduction of heat thereto from said top pan; and means for delivering air under pressure to the lower part of the casing.

4. The combination in a burner of a casing; a plurality of superposed pans mounted in said casing and spaced away from the vertical wall thereof; means for delivering fuel to the top pan; and means for delivering air under pressure to the lower part of the casing; with a conduit passing centrally 25 through the pans for conducting air to the central part of the top pan.

5. The combination in a burner of a casing; a plurality of superposed pans mounted in said casing and spaced away from the vertical wall thereof; means for delivering fuel to the top pan; means for delivering air under pressure to the lower part of the casing; a conduit passing through the pans for conducting air to the central part of the 30 top pan; and a deflector mounted adjacent the lower end of said conduit for imparting a rotary movement to the air flowing between the pans and the wall of the casing.

6. The combination in a burner of a casing; means for delivering air under pressure to the interior of the casing; two pans mounted in the casing and spaced away from the wall thereof, the top pan being spaced away from the bottom of the lower 45 pan to provide a dead air space; means for delivering fuel to the top pan; with a heat

insulating medium mounted under the lower pan.

7. The combination of a casing; a fuel pan mounted therein and spaced away from the wall of the casing; a conduit extending through said fuel pan; means for delivering fuel to the pan; a deflector mounted above said conduit for directing air over the pan; and a source delivering air to the conduit 55 and to the space surrounding the pan.

8. The combination of a casing; a fuel pan mounted therein and spaced away from the wall of the casing; a conduit extending through said fuel pan; means for delivering 60 fuel to the pan; a deflector mounted above said conduit for directing air over the pan; a source delivering air to the conduit and to the space surrounding the pan; with a series 65 of spiral vanes mounted under the pan in position to impart a rotary movement to the air flowing upwardly past the sides thereof.

9. The combination in a burner of a casing; a fuel pan therein; means for delivering fuel to the pan; a source for delivering 70 air under pressure to the bottom of the casing; means for preventing conduction of heat from the bottom of the pan to the air from said source; and a structure for imparting rotary movement to the air as it 75 passes from the source to the sides of the pan.

10. The combination in a burner of a casing; means for delivering air under pressure to the lower part thereof; a hollow refractory gas directing structure mounted on the casing and having an opening thereinto; a fuel pan mounted in the casing below said opening and spaced away from the wall of the casing and also from said refractory 80 structure; means for delivering fuel to the pan; and a conduit passing through the pan and receiving air from the lower part of the casing.

In witness whereof I affix my signature, 90

JOHN W. LEWELLEN
